Patented Mar. 12, 1918.

UNITED STATES PATENT OFFICE.

JESSE SHWAYDER, OF DENVER, COLORADO.

SUITCASE.

1,259,305.

Specification of Letters Patent. Patented Mar. 12, 1918.

Application filed April 8, 1916. Serial No. 89,813.

To all whom it may concern:

Be it known that I, JESSE SHWAYDER, a citizen of the United States, residing at Denver, in the county of Denver and State 5 of Colorado, have invented certain new and useful Improvements in Suitcases, of which the following is a specification.

This invention relates to valises of the type commonly known as suit cases, and 10 its primary object resides in providing a receptacle of this type in which strength and durability are combined with comparatively low cost of production.

Another object of my invention resides in 15 providing novel means for the support of the lid of the case upon the body-portion of the same whereby the parts are tightly joined and braced against collapse.

With the above and other objects in view, 20 all of which will fully appear in the course of the following description, my improved suitcase consists of the arrangement of parts and features of construction illustrated in the accompanying drawings in the 25 various views of which like parts are similarly designated, and in which—

Figure 1 is a top view of a suitcase of the improved construction in an open condition,

Fig. 2, a section taken along the line 2—2,

Fig. 1,

Fig. 3, an enlarged fragmentary, transverse section of the edges of the body and lid of the suitcase at which they are hinged together, the case being in an open condition, and

Fig. 4, a view of the parts shown in Fig. 3 in the relative position they occupy when the case is closed.

Referring to the drawings, the number 2 40 designates the body portion of the suitcase, and 3 the lid of the same. The two members of the case are connected by hinges as at 4 and they are as usual provided with a lock 5, a handle 6 and catches 7.

The body of the case is composed of vul- 45 canized fiber, leather or other material of similar nature, and formed to provide a rec- tangular open receptacle 8.

The sides of the receptacle are reinforced 50 by a wooden frame 9 which extends within the same to within a short distance from its upper edges. A second frame 10 composed of a continuous metal strip bent in conformity with the area of the receptacle, 55 binds the edges of the same and extends con-

tiguously to and above the upper edges of the wooden frame.

The upper edges of the metal frame which lies flat against the inner surfaces of the sides of the receptacle, are folded outwardly 60 over and upon the edges of the same as shown at 12, and the lower edges 13 of the frame are bent inwardly upon themselves for the main purpose of strengthening the structure.

The upper edges of the receptacle are off- 65 set inwardly over the upper edges of the wooden frame and are firmly clamped be- tween the body portion of the metal frame and its folded upper edge, and the parts 70 thus rigidly connected, are covered by a lining 14 made of leather, pantasote, canvas or other suitable material which is glued around the metal frame and upon the inner surface of the wooden frame.

The lid 3 is likewise made of fiber or other 75 similar material formed in correspondence with the body of the case to which it is attached.

The sides 15 of the lid are bound at their 80 edges by a correspondingly formed metal frame 16 the outer edges of which are like those of the frame of the body of the case, folded outwardly over and upon the edges 85 of the sides 15 as shown at 17.

The inner edges of the metal frame 16 which lies flat against the inner surface of the sides of the lid, are bent at right angles to the body portion of the same to provide a continuous flange 18 which when the lid 90 is in its closed position, rests upon the metal frame which constitutes the upper edge of the body of the case.

The metal frame of the lid is covered by 95 a lining 20 of the same material as that which covers the metal frame 10 and the inner surfaces of the body of the case, and both the body and lid are as usual reinforced by corner pieces 19 made of leather or other wear-resisting substance.

When the lid is in its closed position its metal-bound edge overlaps the upper edge 100 of the body of the suit-case, and fits within the space produced by offsetting the upper edges of the fiber walls of the body over the wooden frame which lies flat against the inner surfaces of the same.

The flange 18 of the metal frame of the lid engages as mentioned hereinbefore, the upper edge of the metal frame of the body, 110

and the parts thus support each other against collapse and are tightly joined to protect the contents of the case against dust and moisture.

5 It will be understood that the linings by which the metal and wooden frames are covered, not only give to the case a neat and finished appearance, but materially aid in producing a dust and moisture proof joint 10 when the lid is in the closed position.

Having thus described my invention what I claim and desire to secure by Letters-Patent is:

15 1. A suit-case comprising a box-shaped body part, a lid adapted to close the case, and a frame extending within said body-part along the upper portions of its inner surface, the upper portion of said frame being bent over extending downwardly along 20 the outer surface thereof, the lower portion of said frame being bent upon itself to provide a reinforcing strip.

25 2. A suit-case comprising a box-shaped body part, a lid adapted to close the same, a frame extending within said body part along the upper inner surface thereof, and a second frame positioned within the body-part next to, and so as to cover the inner surface thereof below, and in practical continuation of the upper frame, the upper portion of said first-mentioned frame being bent over the upper edges of said body-part and extending downwardly along the outer surface thereof.

35 3. A suit-case comprising a box-shaped body-part, a box-shaped lid adapted to close the same, said body part being offset adjacent the upper edges of its sides to allow of the lid overlapping the upper edge of 40 the body-part above the offset whereby the overlapping portion is brought within the plane of the body-part; a frame extending

within the body part along the portions of its sides above the offset, and a second frame disposed within the body part so as to cover the portions of its sides beneath the offset, the upper portion of the first-mentioned frame being bent over and extending downwardly along the outer surface of the body-part.

4. A suit-case comprising a box-shaped body part, a box shaped lid, adapted to close the same, said body part being offset adjacent the upper edges of its sides to allow of the lid overlapping the upper edge of the 55 body-part above the offset, whereby the overlapping portion is brought within the plane of the body-part, and a frame extending within the lid along the sides thereof and including an inwardly directed flange 60 which engages the upper edges of the sides of the body part when the lid is in its closed position.

5. A suit-case comprising a box-shaped body part, a box-shaped lid adapted to close 65 the same, said body-part being offset adjacent the upper edges of its sides to allow of the lid overlapping the upper edge of the body-part above the offset, whereby said overlapping portion is brought within the 70 plane of the body-part, a frame within the body-part, bent over and upon the upper edges of its sides, and a frame extending within the lid along the sides thereof and including an inwardly directed flange which 75 engages the upper edges of the sides of the body part when the lid is in its closed position.

In testimony whereof I have affixed my signature in presence of two witnesses.

JESSE SHWAYDER.
